COMPACT

Alfred A. Flaster, New York, N. Y.

Application October 5, 1944, Serial No. 557,321

6 Claims. (Cl. 132—83)

This invention relates to compacts, i. e. cases containing powder, a powder puff and a mirror.

Generally, compact cases are formed of a container and a cover therefor, the container accommodating powder and puff while the cover holds the mirror. The container portion of the compact is made in two different styles as follows.

The most widely used type has a cloth sifter or screen-like fabric secured in the container to hold the powder, the powder puff lying between the sifter and the mirror. This type of compact has the severe disadvantage that powder leaks through the sifter in excess of the desired quantity so as to saturate the puff and on saturation thereof, as well as by working its way around the puff to the top thereof, to spread over the face of the mirror to cloud and obstruct the same.

The other, somewhat improved but also more expensive type of compact has a container portion including two sections, the lower containing loose powder and in place of a sifter, a tightly fitted metal cover or partition cooperating with a felt washer to prevent leakage. This partition is slightly depressed to serve as support for a powder puff lying between the partition and the mirror. This type is superior to the first-mentioned type in that leakage of powder from the lower section of the container is prevented; yet, whenever the puff is saturated with powder it will still cloud the mirror.

Another disadvantage of this type of compact resides in that when the compact is opened only for use of the mirror, e. g. during the application of lipstick or just to check the appearance of the face, the puff, due to the smoothness of the metal surface of the partition, is liable to slide off the partition and drop out of the case. These disadvantages have tended to offset the improvement made in regard to prevention of powder leakage so that this second type of compact, being more expensive than the first without sufficient advantages to justify the added expense, has not found a universal market.

It is an object of the present invention to provide a compact which eliminates the various disadvantages enumerated above, and which is free from powder leakage, clouding of the mirror, or the danger of the puff dropping out of the case.

A further object of the invention is to provide a compact which while eliminating the drawbacks of compacts as heretofore provided, and having other advantages, can be made sufficiently simple and inexpensively as to be available for wide-spread use.

Other objects, and the manner in which the

same are attained, will appear from the following description.

According to the basic concept of my invention, I provide the container portion of my improved compact with a marginal metal portion, approximately of inverted L-section, with a groove in the top of the inverted L; arrange a felt-washer inside this marginal portion and a sifter covering powder held in place by said felt washer; place the puff so that its circumferential portion rests on said felt-washer, the puff thus lying above but spaced from, said sifter; provide a hinged intermediate cover or partition having an outward bulge so as to accommodate the top of the puff, this cover or partition having one projection fitting into the groove arranged in the top part of the inverted L-section, and a second projection abutting against the inverted L-section and pressing down on the circumferential edge of the puff, so as to serve as a double seal, the mirror being mounted in the case cover as usual but due to the arrangement of the partition or intermediate cover above the puff, being shielded altogether from coming in contact with powder from any source, while at the same time, dropping of the puff from the case during use of the mirror alone, is effectively prevented by the intermediate cover. Also, this particular arrangement of the puff results in the puff edges acting as a supplementary gasket which prevents powder from working its way around the puff into contact with the top thereof, contact of the puff with powder being limited to the bottom of the puff exclusively.

In the drawing affixed to this specification and forming part thereof an embodiment of my invention is illustrated diagrammatically in vertical section by way of example.

Referring to the drawing, 1 is the compact case which may consist of metal, plastic or the like and may have a circular or polygonal contour. 2 is a cover which may be hinged to the case and may be fitted inside with a mirror 3. 4 is a marginal insert, e. g. a ring of angular cross section, one flange of which 5 may extend substantially in parallel with the circumferential case wall 6, while the other flange 7 may fit in the case opening in contact with the wall 6 and may be formed with an annular groove 8.

9 is the partition, which may be hinged to the case wall 6 and is formed near its circumferential edge 10 with two concentric, annular projections 11 and 12, the outer projection 11 fitting in the groove 8 of the marginal insert 4, while the inner projection 12 fits tightly against the top portion of the insert 4.

13 is a gasket of felt or similar material encircling the powder compartment 14, and 15 is a puff formed and dimensioned so as to fit tightly in the powder compartment and its wall 5.

As shown in the drawing, the circumferential portion 16 of the puff is forced down on the felt gasket 13 by the inner projection 12 of the partition so as to establish, in conjunction with the projection 11 and the groove 8, a tight double-seal all around the powder compartment. In this manner the powder 17, which is contained in the compartment 14 underneath the sifter 18 and which may pass through the sifter and into contact with the bottom of the puff, is safely prevented from seeping through into the space 14a above the puff. This has the two-fold advantage that not only is the powder prevented from ever reaching and clouding the mirror, but, moreover, the powder is also prevented from reaching and adhering to, the top part of the puff which thus remains free from any powder and when gripped during removal and use of the puff, will not expose hand and clothing of the user to undesirable contact with powder but will safeguard hand and clothing against any powder stains.

I wish it to be understood that I do not desire to be limited to the details shown and described, for obvious modifications within the scope of the appended claims will occur to a person skilled in the art.

I claim:

1. A compact comprising in combination, a cover portion and a container portion, said container portion including a marginal insert, a gasket inside said insert adapted to support the circumferential edge of a puff, a groove in the top of said insert, and an intermediate cover having one projection fitting into said groove, and a second projection overlying and abutting against the side of said insert and adapted to force the circumferential edge of the puff onto said gasket.

2. A compact comprising in combination, a cover portion holding a mirror, and a container portion, said container portion including a marginal insert, a gasket inside said insert, a sifter held between the container bottom and said gasket, a puff adapted to rest on said gasket, a groove in said insert, and an intermediate cover having one projection fitting into said groove, and another projection overlying and abutting against the side of said insert and bearing on said puff, whereby a double-seal seals the container from the cover portion so as to prevent powder from reaching the face of the mirror.

3. In a compact, a container portion, a cover portion, an inner wall in said container portion, a gasket adjoining said inner wall and adapted to support the circumferential edge of a puff, an intermediate cover for sealing said container portion arranged intermediate said container and

cover portions, a projection on said intermediate cover overlying and abutting against the top of said wall, and a second projection on said intermediate cover overlying and abutting against the inner side of said wall and adapted to force said edge on said gasket.

4. A compact comprising in combination, a cover portion and a container portion, a marginal insert in said container portion, a gasket inside said insert adapted to support the circumferential edge of a puff, a groove in the top of said insert, and an intermediate cover arranged intermediate said container and cover portions and having one projection fitting into said groove, and a second projection overlying and abutting against the side of said insert and adapted to force the circumferential edge of the puff on said gasket, said groove and said gasket cooperating with said projections to form a double seal whereby to prevent powder from escaping to said cover portion and to the space between the puff and said intermediate cover, respectively.

5. A compact comprising in combination, a container portion, a cover portion and an intermediate cover portion arranged intermediate said container and cover portions, said container portion including a marginal insert, a gasket inside said insert adapted to support the circumferential edge of a puff, a marginal portion on said intermediate cover having a sealing face bearing on the top of said insert, and a projection on said intermediate cover having a sealing face abutting against the side of said insert, and an additional sealing face bearing on the circumferential edge of the puff to force the same onto said gasket, whereby regardless of wear of the puff edge a multiple seal is maintained so as to prevent powder from escaping from the container portion.

6. A compact comprising in combination, a container portion, a cover portion having a mirror, and an intermediate cover portion arranged intermediate said container and cover portions, said container portion including a marginal insert, a gasket inside said insert adapted to support the circumferential edge of a puff, a sifter held between the container bottom and said gasket, a marginal portion on said intermediate cover having a sealing face bearing on the top of said insert, and a projection on said intermediate cover having a sealing face abutting against the side of said insert, and an additional sealing face bearing on the circumferential edge of the puff to force the same onto said gasket, whereby the puff is prevented from coming in contact with loose powder, regardless of wear of the puff edge a multiple seal is maintained so as to prevent powder from the puff from escaping from the container portion, and consequently clouding of the mirror is eliminated.

ALFRED A. FLASTER.
